TEST EQUIPMENT CONSOLE FOR AN ELECTRICAL EDUCATIONAL KIT

Gerald W. Schmidt, Tarzana, Calif., assignor to International Rectifier Corporation, El Segundo, Calif., a corporation of California

Filed Apr. 25, 1963, Ser. No. 74,603

Term of patent 14 years

(Cl. D26—5)

—FIG. 1—

—FIG. 2—

—FIG. 3—

FIGURE 1 is a perspective view of the test equipment console for an electrical educational kit showing my new design;

FIGURE 2 is a top view thereof; and

FIGURE 3 is a side elevational view.

I claim:

The ornamental design for the test equipment console for an electrical educational kit, as shown.
